Office Action dated May 26, 2022, issued in corresponding Taiwanese Patent Application No. 110306544 with English translation (9 pgs.).

Primary Examiner — Patricia A Palasik

(74) Attorney, Agent, or Firm — Pillsbury Winthrop Shaw Pittman, LLP

(57) **CLAIM**

The ornamental design for a speed reducer, as shown and described.

DESCRIPTION

FIG. 1 is a front perspective view of a speed reducer, showing our new design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings illustrate portions of the speed reducer that form no part of the claimed design.

1 Claim, 8 Drawing Sheets
